UNITED STATES PATENT OFFICE.

BENJAMIN LIPPER, OF PHILADELPHIA, PENNSYLVANIA.

DESIGN FOR BRAID.

SPECIFICATION forming part of Design No. 23,085, dated February 27, 1894.

Application filed January 26, 1894. Serial No. 498,151. Term of patent 3½ years.

To all whom it may concern:

Be it known that I, BENJAMIN LIPPER, a citizen of the United States, residing in Philadelphia, Pennsylvania, have invented a new and original Design for Braid, of which the following is a specification.

My design is fully shown in the accompanying drawing, which represents a strip of the trimming.

10 The design comprises the central openwork band *a* and the edge bands *b*. The band *a* is composed of cross bars *d* and threads *f* intertwined therewith. The edge bands *b* have rows of raised surface stitches or loops *g*, and 15 beyond each band is a looped edging *i*.

The essential features of the design are the bands *a* and *b* of the character shown.

I claim—

The design for trimming substantially as described and as shown in the accompanying 20 drawing.

In testimony whereof I have signed my name to this specification in the presence of two subscribing witnesses.

BENJAMIN LIPPER.

Witnesses:

JOSEPH H. KLEIN,
FRANK BECHTOLD.
